DROP TESTING MACHINE

Leslie G. Freedy, Wauwatosa, Wis., assignor to Vanant Company, Inc., Milwaukee, Wis., a corporation

Application January 4, 1957, Serial No. 632,564

4 Claims. (Cl. 73—12)

This invention appertains to testing apparatus and more particularly to a novel machine for drop testing packed shipping cartons to determine the strength of the package and carton and the amount of abuse the carton and its contents can take when dropped from various heights.

One of the primary objects of the invention is to provide a drop testing machine of an exceptionally simple and durable character and one which can be carried by a wall or partition, so that the machine will occupy a minimum amount of floor space and whereby the use of an expensive supporting frame is eliminated.

Another salient object of the invention is to provide a versatile drop testing machine embodying an upper and a lower horizontal track and spaced vertical tracks each carrying independent drop leaves for supporting a package therebetween, the drop leaves being adjustable on the vertical tracks to position the leaves desired distances from the floor, one of said vertical tracks being slidable on the horizontal tracks to vary the distance between the drop leaves so that cartons of varying lengths can be initially supported by the leaves and whereby packages can be supported either lengthwise or endwise on the leaves.

A further important object of the invention is the provision of means for pivotally mounting the drop leaves on slide brackets carried by the vertical tracks with releasable latches for holding the leaves in a horizontal carton supporting position, and means for simultaneously operating the latches so that the leaves will drop synchronously away from the carton under the weight thereof for permitting the quick flat dropping of the cartons.

A still further object of the invention is the provision of means whereby either latch can be independently operated so that the carton can fall from one end or the other, as may be desired, for testing corner resistance.

A still further important object of the invention is the provision of releasable means for holding the vertical track in any desired position on the horizontal track and for releasably holding the sliding brackets for the drop leaves in any desired adjusted position.

With these and other objects in view, the invention consists in the novel construction, arrangement and formation of parts, as will be hereinafter more specifically described and claimed, and illustrated in the accompanying drawings, in which drawings,

Figure 1 is a front elevational view of the improved drop testing machine showing the same carried by a wall or a partition of a building, the floor of the building being shown in section, the drop leaves being shown in their horizontal carton supporting position in full lines and in their carton dropping position in dotted lines;

Figure 2 is a horizontal sectional view taken on the line 2—2 of Figure 1, looking in the direction of the arrows;

Figure 3 is a vertical sectional view taken on the line 3—3 of Figure 1, looking in the direction of the arrows;

Figure 4 is an enlarged fragmentary detail plan view showing the slide bracket for the adjustable vertical track mounted on the upper horizontal track, parts of this view being shown broken away and in section to illustrate structural detail;

2

Figure 5 is an enlarged fragmentary detail transverse sectional view taken on the line 5—5 of Figure 1, looking in the direction of the arrows and illustrating the releasable means for adjustably holding the slide bracket for the vertical track on the upper horizontal track against movement;

Figure 6 is a detail vertical sectional view taken on the line 6—6 of Figure 3, looking in the direction of the arrows illustrating a detail of construction of the vertical slidable brackets for the drop leaves.

Figure 7 is a detail vertical sectional view taken at right angles to Figure 6 and on the line 7—7 of Figure 6.

Figure 8 is a detail horizontal sectional view illustrating the construction of this slide bracket, the view being taken on the line 8—8 of Figure 7, looking in the direction of the arrows, and

Figure 9 is a detail vertical transverse sectional view taken on the line 9—9 of Figure 3, looking in the direction of the arrows illustrating the construction of one of the releasable latches employed for supporting a drop leaf.

Referring to the drawings in detail, wherein similar reference characters designate corresponding parts throughout the several views, the letter D generally indicates the improved drop testing machine and the same includes an upper horizontal track 10 and a lower spaced track 11. These tracks are located the desired distance apart and the tracks can be secured in spaced relation to a wall or partition 12 by means of bolts 13. Spacing sleeves 14 are interposed between the tracks and the wall so as to insure the proper positioning of these tracks relative to the wall.

The upper track 10 is preferably formed from angle iron or structural steel with one flange of the track projecting outwardly from the wall 12 in a horizontal plane. This flange has welded or otherwise secured thereto, a wear track bar 15. The lower track 11 is also preferably formed from angle iron or structural steel and one flange of this track projects outwardly from the wall in a horizontal plane. Securely fastened to the tracks 10 and 11 at one end thereof is a vertical track 16. This vertical track can be secured at its opposite terminals to the horizontal tracks 10 and 11 by welding, or by bolts 17, as shown. Arranged for sliding movement on the tracks 10 and 11 toward the rigid vertical track 16 is a second vertical track 18. The tracks 16 and 18 are preferably formed from structural steel of a T-shape in cross section. The vertical track 18 is suspended from the upper horizontal track 10, in a novel fashion, as will now be set forth. The upper end of the vertical track 18 has rigidly secured thereto a flat hanger plate 19 which projects outwardly in opposite directions from the track. The ends of the hanger bar have welded or otherwise fastened thereto, such as by bolts 20, inwardly projecting U-shaped slide brackets 21. These spaced slide brackets 21 hook over and slide on the track wear bar 15. The lower end of the track 18 rotatably carries a vertically disposed roller 22 which bears against the horizontal flange of the lower horizontal track 11. By this arrangement the track 18 can be slid along the horizontal tracks toward and away from the rigid vertical track 16. In order to hold the vertical track 18 in a selected adjusted position, the same carries at spaced points turn bolts 23 which can be rotated into and out of binding contact with the track wear bar 15.

The vertical tracks 16 and 18 each carry identically formed slide brackets 24 and 25 and these slide brackets in turn pivotally support like drop leaves 26 and 27. These drop leaves 26 and 27 are normally maintained in a horizontal position, as will be later set forth, for supporting a package or carton that should be tested. The brackets 24 and 25 are movable up and down on their

tracks 16 and 18 so that the cartons supported by the leaves can be positioned in any desired height above a floor.

The brackets 24 and 25 each include a slide face plate 28 for engaging the outer surface of its respective track 16 or 18. Each slide face plate 28 has rigidly secured to its opposite ends C-shaped horizontally disposed slide plates 29 and 30. These C-shaped slide plates 29 and 30 embrace their respective tracks. In order to add rigidity to the slide brackets 24 and 25 at their opposite ends, a clamp block 31 is placed on top of the upper C-shaped slide plate 29 and bolts 32 extend through the clamp block 31, the upper slide plate 29 and into the upper end of the face slide plate 28. Each of the upper C-shaped slide plates 29 carries an outwardly projecting stud 33 and rigidly fastened to each stud by means of a bolt 34 is an outwardly projecting tubular supporting rod 35. The rods 35 rockably support the drop leaves 26 and 27 and the drop leaves are provided with hinge barrels 36 which are rotatably mounted on the rods 35. Stop collars 37 are rigidly fastened to rods and engage the hinge barrels 36 so as to prevent lateral shifting of the drop leaves 26 and 27 on the rods 35. In order to prevent twisting of the rods 35, the same can be braced by struts 38 and these struts extend from the lower C-plates 30 to the rods 35 at a point intermediate their ends.

The brackets 24 and 25 are held in a selected adjusted position on their tracks 16 and 18 in any desired way, and as illustrated the tracks 16 and 18 are provided, each, with a row of equidistantly spaced openings 39. Pins 40 are carried by the slide brackets and these pins can be positioned in selected openings 39.

As heretofore stated, novel means is provided for releasably holding the drop leaves 26 and 27 in their horizontal carton supporting position, and this means includes outwardly projecting arms 41 which extend along the inner edge of the drop leaves. These arms are rigidly fastened to the rods 35 against turning movement and the arms carry guides 42 for spring pressed sliding latch bolts 43. The inner ends of the bolts are provided with tapered noses 44 and the outer ends of the bolts carry rings 45. The opposite ends of a pull chain 46 are connected to the rings 45 so that when a pull is exerted on the chain 46 both of the latch bolts 43 will be synchronously actuated against the tension of their springs. The inner corners of the leaves 26 and 27 rotatably carry laterally projecting rollers 47 and these rollers are adapted to normally rest on top of the latch bolts. When the latch bolts are withdrawn from below the rollers by means of a pull on the chain 46 the drop leaves 26 and 27 will immediately fall away from a package being supported thereby. Thus, the package can be quickly and evenly dropped for flat testing. As soon as the package or carton is dropped, the chain 46 is released and when the drop leaves are more or less lifted to their horizontal positions, the rollers 47 will engage the tapered noses 44 of the bolts 43 and snap back these bolts so that the rollers will ride past the bolts. When this happens, and upon outward sliding movement of the bolts the rollers will again rest on the upper surface of the bolts.

Obviously, by adjusting the vertical track 18 toward and away from the rigid track 16, cartons of different widths can be accommodated, or if desired, the leaves 26 and 27 can be moved close together for supporting a package on its end or away from one another for supporting a package on its side. If such should be desired, one selected bolt 43 can be actuated by grasping the chain nearer that bolt, and in this case only one leaf will be dropped allowing a package to fall on a corner.

From the foregoing description, it can be seen that I have provided a simple machine which can be easily and quickly adjusted for height and also for the length or width of a package.

Changes in details may be made without departing from the spirit or the scope of this invention, but what I claim as new is:

5 1. A drop testing machine comprising spaced horizontally disposed guide tracks, a pair of vertical guide tracks, means for adjusting at least one of the vertical guide tracks on the horizontal guide tracks toward and away from the other vertical guide track, slide brackets on said vertical tracks, carton supporting drop leaves rockably carried by the slide brackets, means adjustably securing the slide brackets in a selected position on the vertical tracks for disposing the drop leaves at a desired distance from a floor, at least one of said drop leaves being movable with a vertical track toward and away from the other drop leaf for receiving packages of different lengths, and means for releasably holding the drop leaves in a horizontal carton supporting position.

20 2. A drop testing machine comprising an upper and a lower horizontal track, means rigidly securing the tracks to a supporting surface, a vertical track rigidly secured to the horizontal tracks at one end thereof, a second vertical track slidably on the horizontal tracks toward and away from the rigid track, means releasably holding the adjustable vertical track in a selected position, slide brackets 25 movable up and down on the vertical tracks, means releasably securing the slide brackets on the vertical tracks in a selected adjusted position, outwardly projecting rods carried by the slide brackets, drop leaves rotatably mounted at their outer edges on said rods, releasable latches for supporting the drop leaves in a horizontal carton supporting position, the distance between said drop leaves being variable by the adjustment of the adjustable vertical track on the horizontal tracks, and means for releasing the latches.

30 3. A drop testing machine comprising an upper and a lower horizontal track, means for securing the tracks rigidly in spaced relation to a support, a vertical track rigidly secured to the horizontal tracks, a second vertical track slidably mounted on the horizontal tracks toward and away from the rigid vertical track, slide brackets carried by the vertical tracks, means holding the slide brackets in a selected adjusted position on the vertical tracks, each of said slide brackets having an outwardly projecting stud, tubular rods receiving the studs and rigidly secured thereto, drop leaves having hinge barrels along one longitudinal edge rotatably mounted on the rods and releasable latches supporting the inner ends of said drop leaves for holding said drop leaves in a horizontal carton receiving position, and means for synchronously operating the latches.

35 4. A drop testing machine comprising an upper horizontal track, a lower horizontal track, means rigidly securing the tracks in spaced relation to a support, a vertical track rigidly secured to and uniting the horizontal tracks, a second vertical track slidably on the horizontal tracks toward and away from the rigid track, means detachably connecting the adjustable vertical track in a selected position on the horizontal tracks, slide brackets mounted on the vertical tracks, means adjustably securing the slide brackets to the vertical tracks, outwardly projecting rods carried by the slide brackets, drop leaves mounted on said rods for swinging movement, supporting arms rigidly secured to said rods and projecting from said rods toward one another, slide latch bolts carried by the arms, means for operating the bolts, and rollers carried by the inner corners of the drop leaves for normally resting upon the upper surface of the latch bolts to hold the drop leaves against swinging movement, said latch bolts being movable from under the rollers to release the drop leaves.
